UNITED STATES PATENT OFFICE.

MATILDE MOISANT, OF LOS ANGELES, CALIFORNIA.

DESIGN FOR A DOLL.

51,988.

Specification for Design.

Patented Apr. 23, 1918.

Application filed February 7, 1918. Serial No. 215,911. Term of patent 7 years.

To all whom it may concern.

Be it known that I, MATILDE MOISANT, a citizen of the United States, residing at Los Angeles, in the county of Los Angeles and State of California, have invented a new, original, and ornamental Design for a Doll, of which the following is a specification, reference being had to the accompanying drawing, forming part thereof.

The figure is a perspective view of a doll, illustrating my new design.

I claim:

The ornamental design for a doll, as shown.

MATILDE MOISANT.

Witnesses:

EDMUND A. STRAUSE,
BERTIN A. WEYL.
